UNITED STATES PATENT OFFICE

147,134

DESIGN FOR A GAME BOARD

William H. Matchett, Auburn, Calif.

Application May 6, 1946, Serial No. 129,354

Term of patent 14 years

(Cl. D34—5)

To all whom it may concern:

Be it known that I, William H. Matchett, a citizen of the United States, residing at Auburn, in the county of Placer and State of California, have invented a new, original, and ornamental Design for a Game Board, of which the following is a specification, reference being had to the accompanying drawing, forming part thereof.

I claim:

The ornamental design for a game board, as shown.

WILLIAM H. MATCHETT.
